UNITED STATES PATENT OFFICE

HARRY C. COLE, OF PHILADELPHIA, PENNSYLVANIA

SPRAYING MACHINE

Application filed November 11, 1931. Serial No. 574,309.

The principal objects of the present invention are to spray any quantity of liquid or fluid of any kind and to control the quantity sprayed even to arresting and restarting the spray, to do this automatically in response to the speed of the machine which feeds the web, sheet or the like which is to be sprayed, and to avoid the use of orifices or the like for controlling the flow of the liquid or fluid that is sprayed by air jets.

Other objects of the invention will appear from the following description.

Generally stated, the invention comprises an inclined sluice at the lower end of which fluid or liquid is continuously discharged, a revolving roller having its curved surface spaced from and rising to a higher level than the discharge end of the sluice and adapted to receive at the ascending portion of its surface the continuous flow from the sluice and to carry over the high part of its surface a portion of the flow fixed by the speed of the roller, the remainder of the flow spilling off the surface of the roller, an inclined gutter at the descending portion of the surface of the roller, and an air jet arranged to discharge across the lower end of the gutter.

The invention also comprises the improvements to be presently described and finally claimed.

In the following description reference will be made to the accompanying drawings forming part hereof and in which

Figure 1 is a plan view with the cover removed.

Fig. 2 is a front view with parts removed and parts in section.

Fig. 3 is a transverse sectional view.

Fig. 4 is a front view showing one of the air passages, and

Fig. 5 is a transverse section of Fig. 4.

There is a series of jets and the device is shown as made in sections, but the following description will be confined to one section and to one jet, the reference characters indicating the similar parts.

1 is an inclined sluice at the lower end of which fluid or liquid is continuously discharged. The fluid or liquid is supplied by 50 a pipe 2 to a reservoir 3 having a baffle 4 and

from this reservoir the fluid or liquid flows in a series of sluices 1. The breasts 5^a at the entrances to the sluices may be made of bakelite or other porous material adapted to insure uniform distribution between the various sluices. 5 is a revolving roller having its curved surface spaced from and rising to a higher level than the discharge end of the sluice 1, and adapted to receive at the descending portion of its surface the continuous flow from the sluice 1, and to carry over the high part or summit of its curved surface a portion of the flow fixed by the speed of rotation of the roller, the remainder of the flow spilling off the cylindrical surface 65 and over the sides of the roller. The receptacle 6 receives the liquid or fluid rejected by the roller and that spills from the roller, and it is conveyed by pipe 7 to the pan 8 from which it can be returned or recirculated through the reservoir 3. 9 is an inclined gutter receiving at the descending portion of the surface of the roller the liquid or fluid carried over the top thereof and varying in quantity according to the speed of rotation 70 of the roller. 10 is an air tube arranged to discharge across the lower end of the gutter and create a spray as indicated in Fig. 3. Air is supplied by pipe 11, through passage 12 to pipe 13 and thence through a hole in pipe 13 and duct 14 to jet 10. The elements 15 are shown as held to place by springs 16. 17 is a cover shown as provided with openings 18 for the passage of the jets. The rollers 5 are mounted on a shaft 19, which can be driven 80 by some part of the machine which feeds the material to be sprayed, so that the quantity of fluid or liquid sprayed is controlled and increased and diminished by the speed of the machine, and when the machine stops the spray stops and when the machine starts the spray starts.

It may be remarked that by reason of the feed of the liquid to the roller 5, the liquid or fluid may be of any character, because it is not picked up or pulled from a body by the roller, but is fed onto the ascending portion of the surface of the roller. Again since the quantity of liquid or fluid diverted to the spray depends upon the speed or revolution 95 100

of the roller, no orifices are employed for controlling the feed and their disadvantages and difficulties are avoided. Inasmuch as the liquid or fluid flows onto the surface of the 5 roller and spills at the ends of the roller and down from the surface, it follows that the roller does not have to separate the liquid or fluid by pulling it from a body of liquid or fluid as would be the case if the roller 10 dipped in a quiescent body of liquid or fluid. Consequently all kinds of fluids or liquids can be employed even those that are relatively viscous.

15 It will be obvious to those skilled in the art to which the invention relates that modifications may be made in details of construction and arrangement and matters of mere form without departing from the spirit of the invention which is not limited to such matters 20 or otherwise than the prior art and the appended claim may require.

I claim:

25 A spraying machine comprising in combination an inclined sluice from the lower end of which fluid or liquid is continuously discharged, a revoluble roller having its curved surface spaced from and rising to a higher level than the discharge end of the sluice and adapted to receive at the ascending 30 portion of its surface the continuous flow from the sluice and to carry over the high part of its surface a portion of the flow fixed by the speed of the roller, the remainder of the flow spilling off the surface of the roller, 35 an inclined gutter at the descending portion of the surface of the roller, and an air jet arranged to discharge across the lower end of the gutter.
